(57) **CLAIM**

The ornamental design for a motorcycle handlebar grip, as shown and described.

DESCRIPTION

FIG. 1 is a perspective view of the motorcycle handlebar grip of the present invention.

FIG. 2 is a first side view thereof, a second, opposite side view being a mirror image thereof.

FIG. 3 is a top view thereof.

FIG. 4 is a bottom view thereof.

FIG. 5 is a first end view thereof; and,

FIG. 6 is a second end view thereof, opposite the first end view.

The motorcycle handlebar grip portions between the grip pads, the grip pads, and the end portions of the motorcycle handlebar grip shown in broken lines form no part of the claimed design.
